[57] **CLAIM**

The ornamental design for a housing for portable data entry terminal, as shown and described.

DESCRIPTION

FIG. 1 is a front, top and left side perspective view of a housing for portable data entry terminal showing my design;

FIG. 2 is a right side elevation view;

FIG. 3 is a bottom plan view;

FIG. 4 is a rear elevation view;

FIG. 5 is a fragmentary top and right side perspective view thereof, the terminal being fragmentarily shown for convenience of illustration;

FIG. 6 is an enlarged fragmentary view of a portion of the top, shown partly in section, as taken along line 6—6 in FIG. 5.
